UNITED STATES PATENT OFFICE.

ALBERT A. GORDON, JR., OF WORCESTER, MASSACHUSETTS, ASSIGNOR TO CROMPTON & KNOWLES LOOM WORKS, A CORPORATION OF MASSACHUSETTS.

LOOM-DOBBY.

935,652.

Specification of Letters Patent.

Patented Oct. 5, 1909.

Application filed November 6, 1906. Serial No. 342,240.

To all whom it may concern:

Be it known that I, ALBERT A. GORDON, Jr., a citizen of the United States, residing at Worcester, in the county of Worcester and 5 State of Massachusetts, have invented certain new and useful Improvements in Loom-Dobbies, of which the following is a specification.

My invention relates to a loom dobby, 10 and particularly to that class of dobbies which have two pattern cylinders having a rotary motion in a fixed plane, and adapted to be operated successively, one pattern cylinder during the weaving of one portion of 15 the fabric, and the other pattern cylinder during the weaving of another portion of the fabric.

The object of my invention is to improve upon the construction of two cylinder dobbies of the class referred to, and more particularly to provide a dobby having two pattern cylinders, and only one set of indicator levers or fingers, to operate the hooks moved by the lifter blades, and direct connections 25 intermediate said two cylinders and the indicator levers or fingers, to cause the movement of said levers or fingers from either pattern cylinder, as desired. When one set 30 of connections, between one pattern cylinder and the indicator levers or fingers, are in operative position, the other set of connections is in inoperative position, and vice versa.

In the preferred construction of my improvements which I have shown in the drawings, I provide a movable frame, over the two pattern cylinders, and intermediate the pattern cylinders, and the indicator levers or fingers which operate the hooks moved by the lifter blades, and I combine with said 40 frame two sets of levers or fingers, termed cylinder fingers, one set operated by one pattern cylinder, and the other set by the other pattern cylinder, and two fingers, one finger of each set adapted to engage and move the 45 same indicator lever or finger.

I provide mechanism, the operation of which is controlled by a pattern chain, to move one set of fingers into operative position, relative to its pattern cylinder and the 50 indicator levers or fingers for the hooks, and to move the other set of fingers out of operative position relative to its pattern cylinder,

and the indicator levers or fingers for the books, and vice versa.

I have only shown in the drawings detached parts of a dobby of the class referred to, embodying my improvements, sufficient to enable those skilled in the art to understand the construction and operation thereof.

Referring to the drawings:—Figure 1 is a 60 partial end view of a two cylinder dobby embodying my improvements, looking in the direction of arrow *a*, Fig. 2; some of the parts are broken away, and other parts are not shown in this figure. Fig. 2 is an edge 65 or side view of the parts shown in Fig. 1, looking in the direction of arrow *b*, same figure. Fig. 3 is a section, on line 3, 3, Fig. 1, looking in the direction of arrow *c*, same figure. Fig. 4 shows, on an enlarged scale, 70 an end view of one cylinder shaft, and disk, and gear, detached, looking in the direction of arrow *d*, Fig. 5. Fig. 5 is a section, on line 5, 5, Fig. 4, looking in the direction of arrow *e*, same figure, and showing in full 75 lines the sleeve carrying a worm and clutch member. Fig. 6 is, on an enlarged scale, a section, on line 6, 6, Fig. 2, looking in the direction of arrow *f*, same figure; this figure shows the pattern chain on each cylinder, 80 and also the lifter blade and hooks, and the connections to the upper hooks, and, Fig. 7 corresponds to Fig. 6, but shows some of the parts in a different position.

In the accompanying drawings, 1 is a detached portion of one end or side of the dobby frame, having a horizontally extending longitudinal slot or opening 1' therein, and the lower lifter bar 2, connected through a link or connector 3 with the rocking lever 85 4. The lower hooks 5, and the upper hooks not shown, through connectors 6, are adapted to be lowered and raised, to be in a position to be engaged by the lifter bar 2, or to be in a position to be out of the path of the lifter 90 bar 2, through the movement of the indicator levers or fingers 7, pivotally mounted on a transverse rod 8, in the usual and well known way. The outer ends of the fingers 7 extend through a grid 9 attached to the 100 dobby frame, and the lower surface of the fingers 7 have a broad foot or engaging surface 7' thereon.

All of the above mentioned parts may be

of the usual and well known construction in the class of dobbies referred to.

I will now describe my improvements.

There are two pattern cylinders 10, and 11, each carrying a pattern surface, in this instance made up of wooden bars 12 linked together, and carrying pattern pins 13. Each pattern cylinder 10, and 11, is fast on a rotary shaft 10', and 11', mounted in suitable bearings 1'' attached to the end frame 1, see Fig. 2, and having a rotary movement in a fixed plane.

On the shaft 14, see Fig. 3, mounted in suitable bearings 14' on hangers connected to the end frame, is fast in this instance a movable, and preferably a rocking frame 16, consisting of two end bars connected by rods 17. The rods 17 in this instance extend above the two cylinders 10, and 11, and upon 20 the outer sides of said cylinders. On the rods 17 are loosely mounted the outer ends or hubs 18' of the cylinder fingers 18.

There are two sets of cylinder fingers 18, one set for each cylinder, and one finger for each row of pattern pins 13, in each pattern chain 12. The inner engaging ends of the cylinder fingers 18 are preferably offset and lap by each other, as shown, and the inner end of each pair of cylinder fingers, one finger for one cylinder, and one finger for the other cylinder, is adapted to engage the same indicator finger 7, on the broadened surface or foot 7' thereon.

When the cylinder fingers 18 are in their lowered position, they rest on the shaft 14.

The rocking motion of the frame 16 in each direction, is in this instance limited by set screws 19 adjustable in a stationary part of the dobby frame, not shown, see Figs. 6, 40 and 7. A rocking motion is communicated to the frame 16, according to the desired movement of the indicator fingers 7, or the pattern to be woven, in this instance through a pattern surface 20, in this instance made up of bars linked together, and carrying rolls 21 and tubes 22, in the usual way, and mounted on a pattern barrel or cylinder 23 fast on a driven shaft 24, operated from some driven part of the loom. The pattern 50 surface or chain 20 operates a pattern lever 25, which is pivoted on a stud 26, see Fig. 1, 25, and has an extension 25', which is connected by an adjustable link 27, with a lever 28, having its hub 28' fast on the shaft 14.

55 The rocking of the shaft 14 and of the frame 16 in one direction, or the other, moves one set of cylinder fingers 18 out of operative position, relatively to the pattern cylinder operating said fingers, and simultaneously moves the other set of cylinder fingers 18 into operative position relatively to the pattern cylinder operating said fingers, see Figs. 6, and 7. In this instance the hub 28' of the arm 28 has a stud 29 extending up 60 therefrom, which is engaged by an elongated

slot 30' in an arm 30, the hub 30'' of which is loosely mounted on a stud 31 on a stationary stand 32, see Fig. 3. The hub 30'' has extending out from opposite sides thereof arms or levers 33, each carrying a stud 33' adapted to extend into an annular groove 34' in a sleeve or collar 34, forming a clutch member, and loosely mounted on the extended hub 38' of gears 38, which gears are loose on the shaft 10' and the shaft 11' of the pattern cylinders 10 and 11. One of the hubs 38' has a worm gear 35 fast thereon, which is adapted to mesh with and be driven by a worm 36 on an upright driven shaft 37, see Figs. 1, and 2. Each gear 38 has an opening 38'' therein.

Fast on the end of each pattern cylinder shaft 10' and 11' is a disk 39, forming a clutch member, and having four openings 39' therein. Each sleeve or collar 34 has a lug or extension 34'' thereon, which extends through the opening 38' in the gear 38, and in the longitudinal movement of the sleeve or collar 34 on the hub 38' of a gear 38, is adapted to enter one of the openings 39' in 90 the disk 39 fast on the shaft 10', or 11', to connect the gear 38 with the shaft, and cause the revolution thereof and of the pattern cylinder fast thereon.

From the above description in connection with the drawings the operation of my improvements will be readily understood by those skilled in the art.

When in the revolution of the pattern chain 20, a roll 21 comes under the foot of 100 the pattern lever 25, through the extension 25', connector 27, and arm 28, the shaft 14 is rocked, and also the frame 16, to move down the outer side or edge of said frame, as shown in Fig. 6, to cause the cylinder fingers 18, extending over the pattern cylinder 10 to be moved into operative position relative to said cylinder, and at the same time to cause the cylinder fingers 18 of the pattern cylinder 11 to be moved out of operative 110 position, as shown in Fig. 6.

The rocking movement of the shaft 14, through the lever 30 and the arms 33 connected therewith, moves one of the clutch sleeves or collars 34, (the one at the right 115 in Fig. 2,) to cause the lug or projection 34'' thereon to enter one of the openings 39' in the disk 39, and clutch or attach the gear 38 to the cylinder shaft 10' of the pattern cylinder 10, to cause the revolution of said 120 shaft and cylinder, through the revolution of the gear 38. At the same time the other clutch sleeve or collar 34 is simultaneously moved, to withdraw the lug or projection 34'' thereon from engagement with the disk 39 fast on the shaft 11' of the pattern cylinder 11, leaving said cylinder at rest, but the gear 38, loose on said shaft 11', is rotated through the worm gear 35, meshing 125 with the worm 36 on the upright driven 130

shaft 37, see Figs. 1, and 3, and said gear 38 meshing with the other gear 38 on the pattern cylinder shaft 10', causes the revolution of said cylinder shaft and pattern cylinder 10 thereon.

When in the rotation of the pattern chain 20 a tube or blank 22 passes under the foot 25' of the pattern lever 25, the pattern lever will drop, and through the action of the 10 spring 40, Figs. 2, and 3, connected with the frame 16, said frame will be moved or rocked in the opposite direction, to move out of operative position the cylinder fingers 18 of the pattern cylinder 10, and move into 15 operative position the cylinder fingers 18 of the pattern cylinder 11, as shown in Fig. 7, and through the movement of the lever 30 and arms 33, the clutch sleeve 34 at the right in Fig. 1, has its lug or projection 34'' 20 moved out of engagement with the disk 39, fast on the pattern cylinder shaft 10', leaving the gear 38 loose on said shaft, and said shaft and the pattern cylinder 10 stationary; at the same time the clutch sleeve 34 on the 25 other cylinder shaft 11' has its lug or projection 34'' moved into engagement with the disk 39 fast on said shaft, to cause the gear 38, operated through the worms 35 and 36, and shaft 37, to rotate the cylinder 30 shaft 11' and the pattern cylinder 11, to operate the cylinder fingers 18 of said cylinder 11, and cause them to operate the indicator levers or fingers 7, as shown in Fig. 7.

The advantages of my improvements will 35 be readily appreciated by those skilled in the art. They are of simple construction and operation, and are adapted to be applied to the ordinary two cylinder dobbies, and by means of my improvements only one set 40 of hook indicator levers, or fingers are employed, the same as in the case of a single cylinder dobby.

It will be understood that the details of 45 construction of my improvements may be varied if desired.

Having thus described my invention, what I claim as new and desire to secure by Letters Patent is:—

1. In a loom dobby, the combination with 50 two pattern cylinders, each carrying a pattern surface, and indicator levers or fingers for operating lifter bar hooks, of a movable frame and two sets of cylinder fingers mounted on said frame, a pair of cylinder 55 fingers, one finger for each cylinder, adapted to engage and move the same indicator lever or finger, and said frame adapted to be moved, to carry one set of cylinder fingers into an inoperative position relative to its 60 pattern cylinder, and the other set of cylinder fingers into an operative position relative to its pattern surface.

2. In a loom dobby, the combination with 65 two pattern cylinders, each carrying a pattern surface, and indicator levers or fingers

for operating lifter bar hooks, of a movable frame, and two sets of cylinder fingers mounted on said frame, a pair of cylinder fingers, one finger for each cylinder, adapted to engage and move the same indicator lever 70 or finger, and said frame adapted to be moved, to carry one set of cylinder fingers into an inoperative position relative to its pattern cylinder, and the other set of cylinder fingers into an operative position relative 75 to its pattern cylinder, and means for moving said frame at predetermined times, and stopping one pattern cylinder and putting into operation the other pattern cylinder.

3. In a loom dobby, the combination with 80 two pattern cylinders carrying pattern surfaces, and indicator levers or fingers for moving the lifter bar hooks, of a rocking frame carrying two sets of cylinder fingers arranged opposite to each other and pivot- 85 ally mounted, and the inner free ends of each pair of cylinder fingers, one finger for each cylinder, adapted to engage and move the same indicator lever or finger, of means for rocking said frame at predetermined 90 times, and moving one set of fingers into an inoperative position relative to its pattern cylinder, to be held in said position, and the other set of fingers into an operative position relative to its pattern cylinder, and 95 means for putting into operation the cylinder for the fingers in operative position, and putting out of operation the cylinder for the fingers in an inoperative position.

4. In a loom dobby, the combination with 100 two pattern cylinders carrying pattern surfaces, and indicator levers or fingers for moving the lifter bar hooks, of a rocking frame carrying two sets of cylinder fingers arranged opposite to each other, and pivot- 105 ally mounted, and the inner free ends of each pair of cylinder fingers, one finger for each cylinder, adapted to engage and move the same indicator lever or finger, of means for rocking said frame at predetermined 110 times, and moving one set of fingers into an inoperative position relative to its pattern cylinder, to be held in said position, and the other set of fingers into an operative position relative to its pattern cylinder, and 115 means for putting into operation the cylinder for the fingers in operative position, and putting out of operation the cylinder for the fingers in an inoperative position, said means consisting of a gear on each cylinder 120 shaft, and clutch mechanism for clutching one gear to its shaft, and unclutching the other gear from its shaft, and driving mechanism for rotating said gears.

5. In a loom dobby, the combination with 125 two pattern cylinders having a rotary move- ment in a fixed plane, and each cylinder carrying a pattern surface, and a worm drive for said cylinders, and indicator levers for operating lifter bar hooks, of cylinder 130

fingers or levers for each cylinder, adapted to operate the same indicator lever or finger to move the lifter bar hooks.

6. In a loom dobby, the combination with two pattern cylinders, having a rotary movement in a fixed plane, and each carrying a pattern surface, and a worm drive for said cylinders, and indicator levers for operating lifter bar hooks, of two sets of cylinder fin-

gers or levers, one finger of each set adapted to operate the same indicator lever or finger to move a lifter bar hook, and means for supporting said cylinder fingers and moving them into and out of operative position.
